UNITED STATES PATENT OFFICE

2,547,579

CARBURETOR

Scott F. Hunt, Meriden, Conn., assignor, by mesne assignments, to Niles-Bement-Pond Company, West Hartford, Conn., a corporation of New Jersey

Original application June 17, 1943, Serial No. 491,096; now Patent No. 2,442,046, dated May 25, 1948. Divided and this application July 17, 1946, Serial No. 684,336

3 Claims. (Cl. 261—34)

1

The present application is a division of my application Serial No. 491,096, filed June 17, 1943, which matured into Patent No. 2,442,046, issued May 25, 1948.

This invention relates to carburetors for internal combustion engines, and particularly to means for operating such carburetors so as to provide improved acceleration characteristics of the engine.

It has previously been proposed to provide, in a carburetor for an internal combustion engine, a device responsive to the pressure in the air induction system at a point downstream from the throttle, and effective upon an increase in such pressure, such as accompanies a sudden opening movement of the throttles, to inject into the air stream an additional supply of fuel so as to rapidly accelerate the engine.

It has been found that with devices of the type described, the additional supply of fuel provided is not always sufficient to complete the acceleration of the engine to a speed corresponding to the new throttle position. Such a device provides a momentary additional supply of fuel for the engine, but it has been found that this additional supply of fuel may be completely dissipated before the acceleration of the engine is completed.

It is therefore an object of the present invention to provide improved means for supplying additional fuel to an internal combustion engine during acceleration of the engine.

A further object of the invention is to provide an improved fuel supply system for an internal combustion engine wherein a first device is used to give an increased fuel supply immediately in response to acceleration of the engine, and a second device is used to provide another additional fuel supply after a time delay following the initiation of a period of acceleration.

A further object of the present invention is to provide improved means for supplying additional fuel to an internal combustion engine upon acceleration, comprising a valve connected in parallel with a fuel regulating valve and controlled as an incident to acceleration of the engine. A still further object is to provide, in such an arrangement, a fuel reservoir having an outlet controlled by an acceleration responsive valve and an acceleration responsive pump for emptying the reservoir. A still further object is to provide such an arrangement in which the valve is maintained open for a period of time longer than that required for the pump to empty the reservoir.

2

Other objects and advantages of the present invention will become apparent from a consideration of the appended specification, claims, and drawing, in which,

The single figure illustrates, somewhat diagrammatically, an aircraft carburetor embodying the principles of my invention.

Referring to the drawing, there is shown a portion 150 of a carburetor body having extending therethru an air passage generally indicated at 154. Air enters the passage at an inlet 152, flows thru a Venturi restriction 153, past a throttle 154 and a discharge nozzle 155 to an outlet 156.

A second air passage connects the air inlet 152 and the throat of venturi 153. This second air passage may be traced from the inlet 152 thru a plurality of impact tubes 157, a vent ring 158, a conduit 160, an expansible chamber 161, a restriction 162, an expapsible chamber 163, a conduit 164, a valve chamber 165, and a conduit 166 to the throat of venturi 153. As it enters the chamber 165 from conduit 164, the air flowing thru this second passage flows past a valve 167 controlled by a bellows 168, which is mounted in the chamber 165. The purpose of the bellows 168 is to compensate the air flow thru this second passage in accordance with variations in density of the flowing air.

The chambers 161 and 163 are part of a metering unit 170, which includes a casing 171 separated by a pair of transverse diaphragms 172 and 173 into expapsible chambers 161, 163 and 174. A motion transmitting member 175 is attached to the center of diaphragm 172, and acts against the center of diaphragm 173. The center of diaphragm 173 is thereby moved to close or open a valve port 176 in the housing 171. A spring 177 biases the member 175 toward a position wherein the valve port 176 is closed by the diaphragm 173.

The fuel supply to the carburetor passes from a pump or other source of fuel under pressure (not shown) thru a fuel regulator unit 178, a conduit 180, a mixture control unit 181, a jet system 182, a conduit 183, a pressure regulator 184, and a conduit 185 to the discharge nozzle 155.

The fuel regulator unit 178 comprises a housing 186 separated by a diaphragm 187 into a pair of expapsible chambers 188 and 190. The diaphragm 187 carries at its center a balanced valve 191, which controls the flow of fuel from the conduit 179 thru the chamber 190 to the conduit 180. A compression spring 192 biases the valve 191 for movement toward open position.

The position of valve 191 is determined by the difference between pressure in the chambers 188 and 190 and by the force exerted by the spring 192. The chambers 188 and 190 are connected by a restriction 193.

A portion of fuel entering the chamber 190 flows thru the restriction 193, chamber 188, conduit 250, expandable chamber 174 of metering unit 170, and a conduit 200 to an opening 201 in the wall of air passage 151.

The mixture control unit 181 includes a disc valve 262 fixed on a shaft 203. The shaft 203 may be manually rotated, by means not shown, so that the disc 262 controls the flow of fuel from the conduit 180 to a pair of conduits 204 and 205 leading to the jet system 182. When the shaft 203 is in a position so that fuel can flow only thru the conduit 205 and not thru conduit 204, the mixture control is said to be in the "lean" position. When the disc valve 202 is in a position such that fuel can flow thru both conduits 204 and 205, the mixture control is said to be in the "rich" position.

The conduit 205 conveys fuel to a pair of restrictions 206 and 207 in the jet system 182. The restriction 206 is fixed. The restriction 207 is normally closed by a valve 208 which is biased to closed position by a spring 210. The conduit 204 conveys fuel thru a restriction 211 in the jet system 182. All fuel passing thru the restrictions 207 and 211 must pass thru another restriction 212 before emerging from the jet system into the conduit 183.

The pressure regulator unit 184 comprises a casing 213 divided by a flexible diaphragm 214 into a pair of expandable chambers 215 and 216. The conduit 183 is connected to the chamber 216, and a balanced valve 217 attached to the center of the diaphragm 214 controls the passage of fuel from the chamber 216 to the conduit 185. A compression spring 218 biases the valve 217 toward its closed position. A conduit 220 connects the chamber 215 to the conduit 160 and thence to the vent ring 158.

The carburetor is provided with an acceleration control including an acceleration pump 251, an acceleration responsive valve 252, and a conduit by-passing the pressure regulator 184. The conduit by-passing the regulator 184 may be traced from circuit 183 thru a conduit 253, a check valve 254, a conduit 255, valve 252, and a conduit 256 to an outlet 259 in the passage 151.

The acceleration pump 251 includes a housing 257 separated by a diaphragm 258 into a pair of expandable chambers 260 and 261. A compression spring 262 biases the diaphragm 258 in a direction to expand the chamber 260 and to collapse the chamber 261. The chamber 261 is connected thru a conduit 263 to the conduit 255. The chamber 260 is connected thru conduit 264 to the air passage 151 at a point on the downstream side of throttle 154.

The acceleration responsive valve unit 252 includes a housing 265 separated by a diaphragm 266 into expandable chambers 267 and 268. A compression spring 270 biases the diaphragm 266 in a direction to expand chamber 267 and to collapse chamber 268. A valve 271 is attached to the diaphragm 266 and cooperates with a seat 272 formed in the housing 265.

The chamber 268 is connected thru a conduit 273 to the conduit 264 and thence to the air passage 151. The chamber 267 is connected thru a restriction 274 to the conduit 264.

Operation

The operation of the carburetor will first be considered under conditions of constant throttle position, so that the acceleration control is not operating. Under these conditions, the pressure differential established between the inlet 152 and the throat of venturi 153 is communicated to the chambers 161 and 163 of metering unit 170. This pressure differential acts upwardly on the member 175, and therefore tends to move the diaphragm 173 in a direction to close the port 176. This upward force is opposed by the pressure of the fuel in the chamber 174. As the member 175 moves upwardly, the port 176 becomes more restricted, and the pressure in chamber 174 increases. As the movement of member 175 continues, a point is reached where the downward force due to the pressure in chamber 174 balances that due to the pressure differential between the chambers 161 and 163, and the member 175 remains in that position. It may therefore be seen that a pressure is established in chamber 174 which is a measure of the mass of air flowing thru the passage 151. This pressure in chamber 174 is communicated back thru conduit 250 to chamber 188 of the fuel regulator 178.

The pressure in chamber 188 acts on the valve 191 in an opening direction, being aided by the spring 192 and opposed by the pressure in chamber 190. As the valve 191 is moved by a change in the pressure in chamber 188, the pressure in chamber 190 is varied in a sense to oppose the pressure change in chamber 188. Therefore as the movement of valve 191 continues, a position is reached at which the pressures in chambers 188 and 190 balance each other and the force of spring 192, and the valve 191 remains in that position. It may therefore be seen that the fuel flow thru the valve 191 is regulated in accordance with the pressure in chamber 188, which is in turn controlled by the mass of air flowing thru the passage 151.

The mixture control unit 181 is provided to permit the operator of the aircraft in which the carburetor is installed, to select either a rich or lean mixture, depending upon the conditions under which the aircraft is operated. The mixture control unit also may be used by the operator to completely cut off the supply of fuel to the carburetor when it is desired to stop the engine.

The jet system 182 provides a fixed restriction in the fuel line. In accordance with well-known hydraulic laws, the flow thru such a fixed restriction is a function of the pressure differential across it. The pressure regulator 184, as described in more detail below, operates to maintain a substantially constant outlet pressure on the jet system 182. Therefore the fuel flow thru the jet system, and hence the flow to the carburetor is controlled by the fuel regulator unit 178, which establishes the fuel pressure on the inlet side of the jet system 182 as a function of the air flow thru the passage 151.

The valve 208 operates to automatically enrich the mixture supplied to the engine under conditions of relatively heavy load. Such heavy load conditions are accompanied by high rates of air flow thru the passage 151, which in turn cause a high pressure differential across the jet system 182. When this pressure differential exceeds a value determined by the strength of spring 210, the valve 208 opens, thereby increasing the quantity of fuel flowing in proportion to the quantity of air.

In the pressure regulator unit 184, the pressure in chamber 216 is balanced against the pressure in chamber 215 and the force of spring 218. The pressure in chamber 215 is relatively low compared to that in chamber 216 and to the force of spring 218. Therefore the variations of pressure in chamber 215 have relatively little regulating effect on the position of valve 217, and the unit operates to maintain a substantially constant pressure in chamber 216. Since the valve 217 is balanced against the pressure at its outlet, the variations in pressure adjacent the discharge nozzle 155 are prevented from affecting the quantity of fuel supplied to the engine. The connection of chamber 215 through conduit 223 to vent ring 158 is chiefly for the purpose of venting the chamber 215 so as to permit ready movement of the valve 217.

The pressure downstream from the throttle in the carburetor is communicated to chamber 260 of accelerating pump 251, while the chamber 261 is subject to the relatively higher fuel pressure on the outlet side of jet system 182. The diaphragm 258 is therefore moved upwardly expanding chamber 261 and filling it with fuel. Since both chambers 267 and 268 of the valve unit 252 are connected to conduit 264, the pressures on the opposite sides of diaphragm 266 are balanced and the valve 271 is closed by the spring 270.

When the throttle 154 is opened, the pressure downstream from it increases, and this increased pressure is transmitted thru conduit 264 to the chamber 260 of pump 251 and chamber 268 of valve 252. This increased pressure is also transmitted to chamber 267 of valve 252, but its transmission to that chamber is delayed by the restriction 274. Therefore the pressures in the chambers 267 and 268 are unbalanced and the higher pressure in chamber 268 causes the valve 271 to open and remain open for a time determined by the size of restriction 274.

At the same time, the increased pressure in chamber 260 causes that chamber to expand, collapsing the chamber 261 and expelling the fuel therefrom. The check valve 254 then closes, and the fuel expelled from chamber 261 is thereby forced thru the valve unit 252 to the outlet 259. The size of restriction 274 is preferably chosen so that the valve 271 remains open for a longer time than that required to empty the chamber 261. As the chamber 261 is emptied, the check valve 254 again opens because of the fuel pressure under it, and an additional supply of fuel taken from the downstream side of the jet system 182 is then by-passed thru the valve 271 to the discharge nozzle 259.

Upon a closing movement of the throttle 134, the decreased pressure on the downstream side of it is communicated to chamber 260 thereby collapsing that chamber and expanding the chamber 261 so that the latter is filled with fuel taken from the downstream side of the jet system 182 thru the conduit 253 and check valve 254. This provides a robbing action by which the supply of fuel to the engine is temporarily decreased below the proportion indicated by the quantity of air flowing thru passage 151. This robbing action enables the engine to decelerate more quickly following the closing movement of the throttle 154.

Since the fuel supply for the acceleration control system is taken from the downstream side of the mixture control valve 181, the movement of the valve 181 to its cut-off position will effec-

tively stop all fuel flow to the engine. Even though the valve 252 or the pump 251 may be faulty or leaky, the fuel flow to the engine may be completely cut off by the operation of valve 181.

While I have shown and described certain preferred embodiments of my invention, other modifications thereof will occur to those skilled in the art, and I therefore intend that my invention shall be limited only by the appended claims.

I claim as my invention:

1. In a carburetor for an internal combustion engine having an air passage and throttle therefor, and a main conduit for conveying metered fuel to said passage with valve for controlling the flow therethru, an acceleration pump comprising an expansible fuel chamber supplied with metered fuel from said main fuel conduit and adapted to discharge said fuel into said air passage, independent of said fuel control valve, incident to an opening movement of said throttle, a second valve for controlling the discharge of fuel from said fuel chamber, a first expansible air chamber having an intermediate wall adapted to collapse said fuel chamber so as to discharge the fuel therein, and means including a second expansible air chamber having a movable wall adapted to operate said second fuel valve, said expansible air chambers being connected to each other thru a metering restriction and to said air passage posterior to said throttle, whereby, upon a rapid opening of said throttle, said second valve is held open for a longer period of time than is required to collapse said expansible fuel chamber, so that an initial discharge thru said second valve at relatively high pressure is followed by a continuing discharge at a relatively low pressure.

2. In a carburetor for an internal combustion engine, in combination, passage means for the air flowing through said carburetor, a throttle for controlling the flow of air through said passage means, first and second fuel conduits for conveying fuel to said air passage, first valve means in said first fuel conduit and second valve means in said second fuel conduit, for respectively controlling the fuel flows therethrough, an expansible fuel chamber connected to said second fuel conduit at a point upstream from said second valve means, a check valve in said second fuel conduit for preventing fuel discharge from said chamber except through said second valve means; a first expansible air chamber having an intermediate wall adapted to collapse said fuel chamber so as to discharge the fuel therein, and means including a second expansible air chamber having a movable wall adapted to operate said second valve means, said expansible air chambers being connected to each other through a metering restriction and to said air passage posterior to said throttle, whereby said second valve means is held open for a period of time longer than that required to collapse said fuel chamber, so that upon a rapid opening of said throttle, an initial fuel discharge through said second valve means from said fuel chamber at relatively high pressure is followed by a continuing discharge through said second valve means from said first conduit at relatively low pressure.

3. In a carburetor for an internal combustion engine, in combination, passage means for the air flowing through said carburetor, a throttle for controlling the flow of air through said passage means, a first fuel conduit for conveying fuel to said air passage, first valve means in said

7 conduit for controlling the flow of fluid therethrough, a second fuel conduit connected to bypass said first valve means, second valve means in said second conduit, an expansible fuel chamber connected to said second conduit upstream from said second valve means, a check valve in said second conduit for preventing fuel discharge from said chamber except through said second valve means, and means operative as an incident to a rapid opening movement of said throttle to open said second valve means and to collapse said chamber so as to discharge said fuel therein, and upon a rapid closing movement of said throttle, to cause immediate closure of said second valve and expand said chamber, so as to tem- 15

porarily reduce the flow of fuel through said first fuel conduit.
